UNITED STATES PATENT OFFICE.

ELWOOD H. MICHENER, OF WOODLYNNE, NEW JERSEY, ASSIGNOR TO ACME STAPLE COMPANY, OF CAMDEN, NEW JERSEY, A CORPORATION OF NEW JERSEY.

STAPLING-MACHINE.

1,363,744.

Specification of Letters Patent. Patented Dec. 28, 1920.

Application filed November 1, 1919. Serial No. 335,042.

To all whom it may concern:

Be it known that I, ELWOOD H. MICHENER, a citizen of the United States, residing at Woodlynne, in the county of Camden, 5 State of New Jersey, have invented certain new and useful Improvements in Stapling-Machines, of which the following is a full, clear, and exact description, reference being had to the accompanying drawings, forming 10 a part of this specification.

This invention relates to improvements in staple setting machines wherein are employed a staple setting anvil, a member movable toward and from the anvil and provided with staple guiding means and a staple driver adapted to coöperate with the staple guiding means and the anvil to set a staple in work placed upon the anvil.

An object of the invention is to provide 20 a novel and advantageous means for controlling and actuating the staple driver under a pressure which will yield during the staple setting operation to compensate for different thicknesses of work placed 25 upon the anvil; and which may be adjusted to provide different degrees of light yielding pressure for fine or thin or delicate work and different degrees of heavy yielding pressure for thick or coarse work to 30 compensate for slight differences in thicknesses in work being stapled by staples having prongs of uniform length, and to provide the desired different yielding pressures 35 for different staples having prongs of varying lengths for work of greater differences in thickness. Another object of the invention is to provide a novel arrangement of parts which will prevent more than one staple 40 at a time from being presented from the staple magazine to the staple driver between it and the anvil; and a further object of the invention is to provide a novel and advantageous means for adjustably supporting the staple clenching anvil.

With the above and related objects in view the invention consists in the novel construction, combination and arrangement of parts hereinafter described and claimed.

In the accompanying drawings illustrating my invention,

Figure 1 is a side view of a stapling machine embodying my invention.

Fig. 2 is a top view thereof.

Fig. 3 is a front view thereof.

Fig. 4 is a vertical section, on line 4—4 55 of Fig. 3, omitting the driving pulley.

Fig. 5 is a vertical section through the driving mechanism, on line 5—5 of Fig. 4.

Fig. 6 is a side view of the driving member detached from the machine. 60

Fig. 7 is a view of one end of the driving member.

Fig. 8 is a view of the other end of the driving member.

Fig. 9 is a sectional detail showing a part 65 of the driving member, a part of the driving pulley and the dog for connecting them.

Fig. 10 is a face view of the boss or hub of the driving pulley provided with the notches to receive the pivoted dog of the 70 driving member.

Fig. 11 is a vertical section through the forward end of the pivoted member carrying the staple driver, on line 11—11 of Fig. 3. 75

Fig. 12 is a detail in section of the staple setting anvil and a part of its supporting bracket.

Referring to the drawings, the frame of the machine comprises a standard 2 provided on its upper portion with a forwardly extending arm 3 and on its lower portion with base projections 6 adapted to be secured to a suitable table 7 for supporting the machine. 80

Pivoted at 8, to the standard 2 is a member 9 which extends forwardly from its pivot laterally adjacent to but spaced from the frame arm 3. The outer side of the member 9 is grooved forming a magazine 90 10 for the staples, and the magazine 10 is provided with a longitudinally-extending guiding rib 12 embraced by the row of staples 13 which is adapted to be fed forwardly thereon toward a wall 14 which is 95 opposite to and spaced from the forward end of the rib 12 a distance equal to the thickness of a staple. The row of staples 13 is fed toward the wall 14 by a suitable follower 15 which is slidably fitted to the 100 magazine 10 and attached to one end of a spring 16 which extends around a pulley 17 and through an opening in the member 9 to a lug 18 on the opposite side of the mem-

ber 9 to which the other end of the spring 16 is attached, the spring 16 acting to move the follower 15 and row of staples 13 toward the wall 14.

5 The space between the wall 14 and the forward end of the staple guiding rib 12 forms part of a channel 19 which extends up and down transversely to the rib 12 and through upwardly and downwardly extending projections 20 and 21, respectively, on the forward end of the member 9. The projection 21 is located above a staple setting anvil 22 which is carried by a bracket 23 secured to the forward end of the frame arm 15 3; and the member 9 is adapted to be moved on its pivot 8 to move the bottom of the projection 21 toward and from the anvil 22 to clamp the work to be stapled between the anvil 22 and the projection 21 during the 20 stapling operation and to raise the projection 21 from the anvil 22 to permit the removal of the stapled work and the insertion of new work to be stapled. When the pivoted member 9 is raised, its upward movement is limited by a projection 24 thereon 25 engaging an adjustable screw 25 which is carried by a lug 26 on the standard 2. By adjusting the screw 25 the extent of the upward movement of the member 9 may be 30 nicely regulated.

A staple driving plate 27 is fitted to slide in the channel 19 toward and from the anvil 22. The staple driver 27 is secured to and extends downwardly from a block 28 which 35 is fitted to slide within the projection 20, and the sides of the block 28 are pivotally connected to the bifurcated end of the forward arm 29 of a lever 30 which embraces the upwardly extending projection 20 of the pivoted member 9. The lever 30 is fulcrumed, at 31, within the bifurcated upper 40 end of a link 32 whose lower end is pivoted, at 33, to the standard 2. The end of rearward arm 34 of the lever 30 is bifurcated and embraces and is pivoted, at 35, to the forward portion of a lever 35 which is fulcrumed at 36 on the upper end of an arm 37 which is also embraced by the lever arm 34. The lower portion of the arm 37 surrounds and is fitted to an eccentric 38 forming part of a driving member 39 which is 50 mounted to turn freely on a shaft 40 projecting fixedly from one side of the standard 2. One end of the shaft 40 is inserted into a split boss 41 on the standard and firmly clamped therein by a screw 42 which is arranged to draw the sides of the split boss 42 together. The lever 35 has an arm 43 which extends rearwardly from its fulcrum point 55 46 and which has a longitudinal slot 44 formed therein. The bottom wall of the slot 44 has spaced notches 45 for the reception of a pin 46 which extends transversely through the slot 44. The outer ends of the pin 46 enter the sides of a split adjusting

member 47 which embraces the bottom portion of the lever arm 43. The adjusting member 47 is connected to the upper end of a spring 48 whose lower end is connected to a projection 49 on the lower portion of the 70 arm 37. The spring 48 tends to draw the lever arm 35 and its fulcrum 36 toward the eccentric 38 and thereby tends to raise the lever arm 34 which is pivoted to the lever 35 forwardly of its fulcrum 36, for a purpose 75 hereinafter explained.

From the construction just described, it will be understood that when the driving member 39 is rotated upon the shaft 40 the eccentric 38 will raise and lower the arm 80 37 and lever 35 and thereby rock the lever 30 and reciprocate the block 28 and staple driver 27.

Mounted to turn loosely on the shaft 40 between the driving member 39 and a collar 51, fixed on the outer end of the shaft, is a pulley 52 which is adapted to be constantly driven in the direction of the arrow in Fig. 1 from any suitable source of power. The inner end of the pulley hub 53 has a circular cavity 54 formed therein into which one end of the driving member 39 extends. The pulley hub 53 is adapted to rotate around the end of the driving member 39, and the hub 53 has a series of spaced outwardly-extending notches 55 which interrupt the circular wall of the cavity 54. The notches 55 are adapted to be entered by the free end of a dog 56 which is pivoted, at 57, to the driving member 39 and which is fitted to a slot 60 100 in the member 39 to move inwardly and outwardly on its pivot 57. Arranged within an opening in the dog 56 is a spring 61 which presses against the member 39 and dog 56 and tends to force the free end of the dog 105 outwardly. Normally the dog 56 is held in its innermost position, as shown in the drawings, against the spring 61 by a cam 62 formed on a controlling part 63 which is pivoted, at 64, to the standard 2. When the 110 part 63 is rocked on its pivot 64 in the direction of the arrow in Fig. 4, to move the cam 62 from beneath the dog 56, the dog 56 will be freed and forced by the spring 61 against the circular wall of the cavity 115 54; and, thereafter, the dog 56 will be forced by the spring 61 into the first notch 55 of the constantly rotating pulley 52 which passes it. Immediately upon the entrance of the dog 56 into the notch 55, the driving member 39 will start to rotate with the pulley 52 and will continue to rotate therewith until the controlling part 63 is returned to the position shown in Fig. 4, as will be herein-after explained. The driving member 39 120 has an outwardly extending ring or flange 65 formed thereon and cut away to form a shoulder 66 to be engaged by a projection 67 on the controlling part 63 to stop the rotation of the driving member 39 when the 125 130

controlling part 63 is returned to its normal position. The controlling part 63 has an arm 68 formed thereon which is adapted to engage a lug 69 projecting from the standard 2 to stop the further movement of the part 63 after it has been moved in the direction of the arrow sufficiently to cause the cam 62 and projection 67 to clear the dog 56 and tooth 66, respectively, and thereby permit 10 the driving member 39 to be rotated by and with the pulley 52. When the controlling part 63 is moved to permit this operation the projection 67 clears the shoulder 66 before the cam 62 clears the dog 56 and 15 permits the dog to enter a notch 55 in the pulley hub 53, so that the driving member 39 will be free to rotate immediately the dog enters a notch 55.

To prevent the driving member 39 from 20 being turned backward, I provide it with an opening or cavity 70 having a dog 71 slidably fitted therein. The dog 71 and the adjacent wall of the opening 70 are made square in cross section to prevent the dog 25 from turning; and the dog is provided with an inwardly projecting pin 72 which is encircled by a spring 73 which presses the dog 71 against the frame boss 41. The outer end of the dog 71 is beveled as shown and enters a similarly shaped notch 74 in the 30 frame boss 41 after each revolution of the driving member 39 and thereby prevents backward turning thereof. When the driving member 39 is turned forwardly by the pulley 52, the dog 71 is forced by its beveled end out of the notch 74 against the action of the spring 73.

The pivoted member 9 is adapted to be lowered toward the anvil 22, and the controlling part 63 is adapted to be moved in the direction of the arrow to start the actuation of the driving member 39 by operating a link 75 which is pivoted, at one end at 40 76, to the controlling part 63 and which extends forwardly therefrom. The forward end of the link 75 is pivoted, at 77, to the lower portion of a link 78 whose upper end is pivoted, at 80, to the member 9. The link 78 extends downwardly from its pivoted connection with the link 75 and into a guiding slot in a lug 81 on the standard 2. The link 75 is held normally elevated in the position shown in the drawings by a spring 82 the lower end of which is connected thereto and 45 the upper end of which is connected to a lug on the standard 2. In holding the link 75 up in the position illustrated, the spring 82 holds the pivoted member 9 elevated and holds the controlling part 63 in position to 50 prevent the rotation of the driving member 39 by the pulley 52. The link 75 is adapted to be depressed by a suitable foot pedal, not shown, connected to a bar 83 whose upper end is pivoted to the link 75. The 55 relation of the connections just described

is such that when the bar 83 is moved downwardly, the first operation effected thereby will be to rock the link 75 on its pivot 76, without moving the controlling part 63 until the link 75 pulls the pivoted member 9 down 70 to engage its projection 21 with the work upon the anvil 22 to be stapled and thereby stop further downward movement of the member 9. When the downward movement of the member 9 is thus stopped, the further 75 downward movement of the bar 83 will rock the link 75 on its pivot 77 and move the controlling part 63 in the direction of the arrow until it engages the stop lug 69 and prevents further downward movement 80 of the bar 83 and releases the driving member 39 and permits the dog 56 to enter a notch 55 of the driving pulley 52 to start the rotation of the driving member 39 by and with the pulley 52. If the bar 83 be 85 depressed to effect the operations just described and released immediately after the member 39 starts to rotate, the spring 82 will return the controlling part to normal position and the controlling part will stop 90 the rotation of the driving member 39 after the pulley 52 turns it a complete revolution.

Slidably fitted within an opening in the lever arm 29 is a pin 84 having a head 85 on the lower end thereof; and encircling the 95 pin 84 and housed within a cavity in the lever arm 29 is a spring 86 which acts between the head 85 and the top wall of the cavity to force the pin 84 downwardly. The downward movement of the pin 84 is 100 stopped by a nut 87 which is screwed on to the upper end of the pin 84 and engages the top of the lever arm 29. The head 85 is arranged directly over an upwardly extending projection 89 on the pivoted arm 105 9, whereby, when the lever arm 29 is lowered, the head 85 will engage the projection 87 and force it and the pivoted member 9 downwardly with a yielding pressure, for a purpose hereinafter explained. By adjusting the nut 87 the head 85 may be adjusted toward or from the projection 87, as desired. A lock nut 88 is provided on the upper end of the pin 84 to be screwed against the nut 87 to lock it in place after adjustment. 110 115

The staple setting anvil 22 has a round pin like extension 90 formed thereon which enters a similarly shaped opening in the bracket 23 and which is firmly held therein by a set screw 91 screwed into the bracket 120 23 and engaging the extension 90. This construction provides a very convenient means for adjustably securing the anvil 22 to the bracket 23. By loosening the screw 91 the extension 90 may be moved longitudinally 125 within its opening in the bracket 23 to adjust the anvil 22 laterally with respect to the staple driver 27 and staple guiding channel 19; and by rocking the anvil 22 on the axis of the extension 90 the grooved 130

top of the anvil may be adjusted forward and back with respect to the staple driver 27 and staple guiding channel 19.

The operation of the machine is as follows:

A supply of staples 13 is placed within the magazine 10 and they are fed up against the staple driver 14 by the action of the spring 16. The pulley 52 is driven constantly from a suitable source of power and the parts of the machine rest normally in the position shown in the drawings while the pulley 52 rotates idly on the shaft 40. The work to be stapled is placed upon the anvil 22 and the bar 83 is depressed against the action of the spring 82 by the aid of a foot pedal or other suitable device, and immediately after the depression thereof it is released. During the initial downward movement of the bar 83 it rocks the link 75 on its pivot 76 and thereby causes the link 75 to pull the pivoted member 9 down until its staple guiding projection 21 rests upon the work placed upon the anvil 22 and prevents further downward movement of the member 9. The engagement of the projection 21 with the work also prevents further downward movement of the pivoted end 77 of the link 75; and, therefore, the continued downward movement of the bar 83 causes it to pull the pivoted end 76 of the link 75 downwardly and thereby rock the controlling member 63 on its pivot 64 in the direction of the arrow in Fig. 4 until it engages the stop lug 69 and prevents further downward movement of the bar 83. When the controlling part 63 is thus moved its arm 67 is first moved outwardly to clear the shoulder 66 to unlock or release the member 39; and, immediately thereafter the cam 62 clears the dog 56 and it enters one of the notches 55 in the hub of the rotating pulley 52, connecting the driving member 39 thereto and causing it to turn therewith. As the dog 56 enters a notch in the pulley 52 almost immediately upon being released by the cam 62, the bar 83 may be released practically immediately after it has been depressed sufficiently far to bring the controlling part 63 into engagement with the stop lug 69. As soon as the driving member 39 starts to turn with the pulley 52 and the bar 83 is released, the spring 82 in tending to raise the link 75 pulls the arm 67 into engagement with the periphery of the flange 65 of the member 39 and prevents the return of the controlling part 63 to its normal position until the driving member 39 makes a complete revolution, whereupon the spring 82 pulls the part 63 back to normal position and causes the arm 67 to engage the shoulder 66 and prevent further turning of the driving member 39 just as the dog 56 is moved by the cam 62 from engagement with a notch 55 in the

driving pulley 52. It will be observed that when the driving member 39 is at rest, the position of its eccentric 38 is such that the staple driver 27 is about midway of its stroke, crossing the feed line of the row of staples 13 in the magazine 10, and that a staple 13^a is in the channel 19 beneath the driver 27, the staple 13^a having been moved there from the row 13 by the driver 27 during its downward movement just before the completion of the turning of the driving member 39 of its last previous revolution. Now, when the driving member 39 turns a revolution, as above described, the eccentric 38, through the arm 37 and levers 35 and 30, depresses the staple driver 27 from the position illustrated, as the high part of the eccentric 38 passes over the shaft 40, then raises the staple driver to its highest position above that illustrated, as the high part of the eccentric 38 moves down to a position beneath the shaft 40, and then depresses the staple driver 27 to the position illustrated, as the eccentric 38 comes to rest with the driving member 39. During the downward movement of the staple driver 27 from the position illustrated, it drives the staple 13^a down through the channel 19 and through the work upon the anvil 22 and into engagement with the anvil causing it to turn the staple prongs inwardly and clench the same. During the reverse or upward movement of the staple driver 27 to its highest point, its lower end passes the top of the row of staples 13 in the staple magazine 10, permitting the spring 16 to feed the foremost staple of the row 13 up against the wall 14 and beneath the bottom of the driver 27, so that when the driver 27 is moved down to the position illustrated it will move the foremost staple of the row 13 down to the position previously occupied by the staple 13^a, for a succeeding stapling operation. It will thus be seen that a staple will be set in work placed upon the anvil 22 each time the bar 83 is depressed to permit the driving member 39 to turn a complete revolution. During the setting of a staple, the downward movement of the staple driver 27 to effect the same is arrested when the top bar of the staple connecting its prongs engages the top of the work placed upon the anvil 22, and this takes place before the high part of the eccentric 38 reaches a position directly over the shaft 40 and before the eccentric arm 37 completes its upward movement. It will be understood, therefore, that as the arm 37 completes its upward movement it will raise the fulcrum 36 of the lever 35 while the staple driver 27 and its actuating lever 30 are thus arrested, causing the lever 35 to rock on its fulcrum 36 against the action of the spring 48 in a manner to cause the staple to be set by a yielding pressure and to

compensate for varying thicknesses within limits in the work placed upon the anvil. To obtain the best results, the pull of the spring 48 upon the lever 35 should be varied when the thickness of the work varies to any appreciable extent, and also staples having prongs of varying lengths should be used, for greatly varying thicknesses of work; the length of the prongs being consistent with the thickness of the work to provide the proper length of prongs which penetrate below the work for clenching and the pull of the spring 48 for stapling thick work being greater than for stapling thin or delicate work, so that the stapling pressure against the driver 27 will not yield before the thick work has been properly penetrated by the staple, and so that the yielding pressure of the staple driver will not be too great for thin or delicate work. This desired yielding pressure or pull of the spring 48 may be varied or regulated by moving the spring connecting member 47 toward and from the lever fulcrum 36, as previously explained.

When the lever arm 29 is moved down to operate the staple driver 27 to set a staple, the head 85 of the spring pressed pin 84 engages the projection 87 on the pivoted member 9 and holds the projection 21 of the member 9 down upon the work being stapled with a yielding pressure.

After the bar 83 has been depressed and released to effect a stapling operation, as previously described, the spring 82 does not raise the pivoted member 9 to the position illustrated until the staple has been set in the work and the lever arm 29 is raised to elevate the staple driver 27 due to the friction between the staple driving parts and the parts of the member 9 which guide them. After the staple has been set, the pivoted member 9 rises to the position illustrated with the lever arm 29 when it elevates the staple driver 27 within the pivoted member 9, the upward movement of the staple driver 27 within the member 9 causing it with the aid of the spring 82 to raise the member 9.

I claim as my invention:

1. In a staple setting machine, the combination of a supporting frame, a staple setting anvil, staple supplying and guiding means, a staple driver adapted to coöperate with said anvil to set a staple, a movable actuating part connected to said driver, a rotatable driving member, an eccentric carried by said member, an arm operatively connected to the eccentric, a lever fulcrumed on said arm and connected on one side of its fulcrum to said actuating part, and a spring acting between a part of the machine and said lever on the other side of its fulcrum to move it toward the eccentric, whereby when the driving member is rotated the

staple driver will be actuated by a yielding pressure.

2. In a staple setting machine, the combination of a supporting frame, a staple setting anvil, staple supplying and guiding means, a staple driver adapted to coöperate with said anvil to set a staple, a movable actuating part connected to said driver, a rotatable driving member, an eccentric carried by said member, an arm operatively connected to the eccentric, a lever fulcrumed on said arm and connected on one side of its fulcrum to said actuating part, and a spring acting between said arm and said lever on the other side of its fulcrum to move it toward the eccentric, whereby when the driving member is rotated the staple driver will be actuated by a yielding pressure.

3. In a staple setting machine, the combination of a supporting frame, a staple setting anvil, staple supplying and guiding means, a staple driver adapted to coöperate with said anvil to set a staple, an actuating lever fulcrumed on a part of the machine and having one arm operatively connected to said driver, a rotatable driving member, an eccentric carried by said member, an arm operatively connected to the eccentric, a lever fulcrumed on said arm and connected on one side of its fulcrum to the other arm of said actuating lever, and a spring acting between a part of the machine and the second named lever on the other side of its fulcrum to move it toward the eccentric, whereby when the driving member is rotated the staple driver will be actuated by a yielding pressure.

4. In a staple setting machine, the combination of a supporting frame, a staple setting anvil, staple supplying and guiding means, a staple driver adapted to coöperate with said anvil to set a staple, an actuating lever fulcrumed on a part of the machine and having one arm operatively connected to said driver, a rotatable driving member, an eccentric carried by said member, an arm operatively connected to the eccentric, a lever fulcrumed on said arm and connected on one side of its fulcrum to the other arm of said actuating lever, and a spring acting between said arm and the second named lever on the other side of its fulcrum to move it toward the eccentric, whereby when the driving member is rotated the staple driver will be actuated by a yielding pressure.

5. In a staple setting machine, the combination of a supporting frame, a staple setting anvil, staple supplying and guiding means, a staple driver adapted to coöperate with said anvil to set a staple, a movable actuating part connected to said driver, a driving member operative to move said part, a lever fulcrumed on said member and connected on one side of its fulcrum to said actuating part, a spring acting between a

part of the machine and said lever on the other side of its fulcrum and causing said member to move said part by a yielding pressure, and adjustable means to vary the pressure of said spring against said part.

6. In a staple setting machine, the combination of a supporting frame, a staple setting anvil, staple supplying and guiding means, a staple driver adapted to cooperate with said anvil to set a staple, a movable actuating part connected to said driver, a rotatable driving member, an eccentric carried by said member, an arm operatively connected to the eccentric, a lever fulcrumed on said arm and connected on one side of its fulcrum to said actuating part, a spring acting between a part of the machine and said lever on the other side of its fulcrum to move it toward the eccentric, whereby when the driving member is rotated the staple driver will be actuated by a yielding pressure, and adjustable means to vary the pressure of said spring against said part.
- 10
- 15
- 20

25 7. In a staple setting machine, the combination of a supporting frame, a staple setting anvil, staple supplying and guiding means, a staple driver adapted to coöperate with said anvil to set a staple, a movable actuating part connected to said driver, a rotatable driving member, an eccentric carried by said member, an arm operatively connected to the eccentric, a lever fulcrumed on said arm and connected on one side of its fulcrum to said actuating part, a spring acting between said arm and said lever on the other side of its fulcrum to move it toward the eccentric, whereby when the driving member is rotated the staple driver will
30 be actuated by a yielding pressure, and adjustable means to vary the pressure of said spring against said part.

35

40

8. In a staple setting machine, the combination of a supporting frame, a stable setting anvil, staple supplying and guiding means, a staple driver adapted to coöperate with said anvil to set a staple, an actuating lever fulcrumed on a part of the machine and having one arm operatively connected to said driver, a rotatable driving member, an eccentric carried by said member, an arm operatively connected to the eccentric, a lever fulcrumed on said arm and connected on one side of its fulcrum to the other arm of said actuating lever, a spring acting between a part of the machine and the second named lever on the other side of its fulcrum to move it toward the eccentric, whereby when the driving member is rotated the staple driver will be actuated by a yielding pressure, and adjustable means to vary the pressure of said spring against said actuating lever.

9. In a staple setting machine, the combination of supporting frame, a staple set-

ting anvil, staple supplying and guiding means, a staple driver adapted to coöperate with said anvil to set a staple, a movable actuating part connected to said driver, a reciprocable element, a lever fulcrumed on 70 said element and connected on one side of its furcram to said actuating part, a spring having one end connected to said element, and means to connect the other end of said spring to said lever on the other side of its 75 fulcrum at different distances therefrom to vary the pressure of the spring against said actuating part, whereby when said element is reciprocated the staple driver will be actuated by a yielding pressure and whereby 80 the yielding pressure may be regulated by adjusting the spring connecting means toward and from the fulcrum of the lever.

10. In a staple setting machine, the combination of a supporting frame a staple setting anvil supported by the frame, a member having a staple guiding channel pivoted on the frame to move toward and from the anvil, a staple driver guided in said member and adapted to coöperate with said anvil to set a staple, a link pivoted on the frame independently of the pivotal bearing of said staple guiding member, and movable relatively thereto, an actuating lever fulcrumed on said pivoted link and connected to the staple driver to move the same relatively to said member to set a staple when the lever is actuated, means operative to move said member toward and from the anvil, and means operative to actuate the lever. 100

11. In a staple setting machine, the combination of a supporting frame a staple setting anvil supported by the frame, a member pivoted on the frame to move toward and from the anvil and provided with staple guiding means, a staple driver guided in said member and adapted to coöperate with said anvil to set a staple, a link pivoted on the frame, an actuating lever fulcrumed on said link and connected to the staple driver to move the same relatively to said member to set a staple when the lever is actuated, means operative to move said member toward and from the anvil, a rotatable driving member, an eccentric carried by the driving member, and connecting actuating means between the eccentric and the lever.

means between the eccentric and the lever.

12. In a staple setting machine, the combination of a supporting frame, a staple setting anvil supported by the frame, a member pivoted on the frame to move toward and from the anvil and provided with staple guiding means, a staple driver guided in said member and adapted to coöperate with said anvil to set a staple, a link pivoted on the frame, an actuating lever fulcrumed on said link and connected to the staple driver to move the same relatively to said member to set a staple when the lever is actuated, means operative to move said member to-

ward and from the anvil, a rotatable driving member, an eccentric carried by the driving member, an arm operatively connected to the eccentric, a lever fulcrumed on 5 said arm and connected on one side of its fulcrum to said actuating lever, and a spring acting between said arm and the second named lever on the other side of its fulcrum to move it toward the eccentric, whereby 10 when the driving member is rotated the staple driver will be actuated by a yielding pressure.

13. In a staple setting machine, the combination of a supporting frame, a staple setting anvil supported by the frame, a member pivoted on the frame to move toward and from the anvil and provided with staple guiding means, a staple driver guided in 15 said member and adapted to coöperate with said anvil to set a staple, a link pivoted on 20 the frame, an actuating lever fulcrumed on said link and connected to the staple driver to move the same relatively to said member to set a staple when the lever is actuated, 25 means operative to move said member toward and from the anvil, a rotatable driving member, an eccentric carried by the driving member, an arm operatively connected to the eccentric, a lever fulcrumed on said arm 30 and connected on one side of its fulcrum to said actuating lever, and means to connect the other end of said spring to the second named lever on the other side of its fulcrum at different distances therefrom to vary the 35 pressure of the spring against said actuating lever, whereby when the driving member is rotated the staple driver will be actuated by a yielding pressure and whereby the yielding pressure may be regulated by adjusting 40 the spring connecting means toward and from the fulcrum of the second named lever.

14. In a staple setting machine, the combination of a supporting frame, a staple setting anvil supported by the frame, a member 45 pivoted on the frame to move toward and from the anvil and provided with staple guiding means, a staple driver guided in said member and adapted to coöperate with said anvil to set a staple, a driving member, means 50 to actuate the driving member, connecting actuating means between the driving member and the staple driver, and additional means operative to move the pivoted staple guiding member toward and from the anvil and 55 to start and stop the operation of the means actuating the driving member.

15. In a staple setting machine, the combination of a supporting frame, a staple setting anvil supported by the frame, a member 60 pivoted on the frame to move toward and from the anvil and provided with staple guiding means, a staple driver guided in said member and adapted to coöperate with said anvil to set a staple, a controlling part

pivoted to the frame, a link having one 65 end pivoted to said part, a second link pivotally connected to the other end of the first named link and to said member, means operative to move the first named link and thereby move said member toward said anvil and thereafter move said part, and means controlled by said part when moved to actuate the staple driver.

16. In a staple setting machine, the combination of a supporting frame, a staple setting anvil supported by the frame, a member pivoted on the frame to move toward and from the anvil and provided with staple guiding means, a staple driver guided in 75 said member and adapted to coöperate with 80 said anvil to set a staple, a controlling part pivoted to the frame, a link having one end pivoted to said part, a second link pivotally connected to the other end of the first named link and to said member, means 85 operative to move the first named link from its normal position and thereby move said member toward said anvil and thereafter move said part, means controlled by said part when moved to actuate the staple 90 driver, and a spring to return the first named link to normal position.

17. In a staple setting machine, the combination of a supporting frame, a staple setting anvil supported by the frame, a member 95 pivoted on the frame to move toward and from the anvil and provided with staple guiding means, a staple driver guided in said member and adapted to coöperate with 100 said anvil to set a staple, a controlling part pivoted to the frame, a link having one end pivoted to said part, a second link pivotally connected to the other end of the first named link and to said member, a bar pivoted to 105 the first named link between its pivoted ends and operative to move the same from its normal position and thereby move said member toward said anvil and thereafter move said part, means controlled by said part when moved to actuate the staple 110 driver, and a spring having one end connected to said frame and the other end connected to the first named link between its pivoted ends to return it to normal position.

18. In a staple setting machine, the combination of a supporting frame, a staple setting anvil supported by the frame, a member pivoted on the frame to move toward and from the anvil and provided with staple guiding means, a staple driver guided in 115 said member and adapted to coöperate with said anvil to set a staple, a movable controlling part, means operative to move said member toward the anvil and thereafter move said part, a shaft, a driving member 120 loosely mounted on said shaft, means controlled by said part when moved to start and stop the rotation of the driving mem-

ber, and connecting actuating means between the driving member and the staple driver.

19. In a staple setting machine, the combination of a supporting frame, a staple setting anvil supported by the frame, a member pivoted on the frame to move toward and from the anvil and provided with staple guiding means, a staple driver guided in 5 said member and adapted to coöperate with said anvil to set a staple, a movable controlling part, means operative to move said member toward the anvil and thereafter move said part, a shaft, a driving member 10 loosely mounted on said shaft, means controlled by said part when moved to start and stop the rotation of the driving member, an eccentric carried by the driving member, an arm operatively connected to 15 the eccentric, and connecting actuating means between said arm and the staple driver.

20. In a staple setting machine, the combination of a supporting frame, a staple setting anvil supported by the frame, a member pivoted on the frame to move toward and from the anvil and provided with staple guiding means, a staple driver guided in 25 said member and adapted to coöperate with said anvil to set a staple, a movable controlling part, means operative to move said member toward the anvil and thereafter move said part, a shaft, a driving member 30 loosely mounted on said shaft, means controlled by said part when moved to start and stop the rotation of the driving member, an eccentric carried by the driving member, an arm operatively connected to 35 the eccentric, a lever fulcrumed on said arm, 40 a spring acting between a part of the machine and said lever on one side of its fulcrum to move it toward the eccentric, and connecting actuating means between said lever on the other side of its fulcrum and the staple driver, whereby when the eccentric is rotated the staple driver will be actuated by a yielding pressure.

21. In a staple setting machine, the combination of a supporting frame, a staple setting anvil supported by the frame, a member pivoted on the frame to move toward and from the anvil and provided with staple guiding means, a staple driver guided in 50 said member and adapted to coöperate with said anvil to set a staple, a movable controlling part, means operative to move said member toward the anvil and thereafter move said part, a shaft, a driving member 55 loosely mounted on said shaft, means controlled by said part when moved to start and stop the rotation of the driving member, an eccentric carried by the driving member, an arm operatively connected to 60 the eccentric, a lever fulcrumed on said arm, 65 a spring acting between a part of the ma-

chine and said lever on one side of its fulcrum to move it toward the eccentric, and a lever fulcrumed on the machine and connected to the first named lever on the other side of its fulcrum and operatively connected to the staple driver, whereby when the eccentric is rotated the staple driver will be actuated by a yielding pressure. 70

22. In a staple setting machine, the combination of a supporting frame, a staple setting anvil supported by the frame, a member pivoted on the frame to move toward and from the anvil and provided with staple guiding means, a staple driver guided in 75 said member and adapted to coöperate with said anvil to set a staple, a movable controlling part, means operative to move said member toward the anvil and thereafter move said part, a shaft, a driving member 80 loosely mounted on said shaft, means controlled by said part when moved to start and stop the rotation of the driving member, an eccentric carried by the driving member, an arm operatively connected to 85 the eccentric, a lever fulcrumed on said arm, 90 a spring, acting between a part of the machine and said lever on one side of its fulcrum to move it toward the eccentric, a link pivoted on the frame, and a lever fulcrumed on the link and connected to the first named 95 lever on the other side of its fulcrum and operatively connected to the staple driver, whereby when the eccentric is rotated the staple driver will be actuated by a yielding pressure. 100

23. In a staple setting machine, the combination of a supporting frame, a staple setting anvil supported by the frame, a member pivoted on the frame to move toward and from the anvil and provided with staple 105 guiding means, a staple driver guided in said member and adapted to coöperate with said anvil to set a staple, a movable controlling part, means operative to move said member toward the anvil and thereafter 110 move said part, a shaft, a driving member loosely mounted on said shaft, means controlled by said part when moved to start and stop the rotation of the driving member, an eccentric carried by the driving member, an 115 arm operatively connected to the eccentric, and a lever fulcrumed on the machine and operatively connecting said arm and the staple driver.

24. In a staple setting machine, the combination of a supporting frame, a staple setting anvil supported by the frame, a member pivoted on the frame to move toward and from the anvil and provided with staple guiding means, a staple driver guided in 120 said member and adapted to coöperate with said anvil to set a staple, a movable controlling part, means operative to move said member toward the anvil and thereafter move said part, a shaft, a driving member 125

loosely mounted on said shaft, means controlled by said part when moved to start and stop the rotation of the driving member, an eccentric carried by the driving member, an arm operatively connected to the eccentric, a link pivoted on the frame, and a lever fulcrumed on the link and operating on one side of its fulcrum to move it toward the eccentric, and connecting actuating means between said lever on the other side of its fulcrum and the staple driver, whereby when the eccentric is rotated the staple driver will be actuated by a yielding pressure.

10 25. In a staple setting machine, the combination of a supporting frame, a staple setting anvil supported by the frame, a member pivoted on the frame to move toward and from the anvil and provided with
15 staple guiding means, a staple driver guided in said member and adapted to coöperate with said anvil to set a staple, a controlling part pivoted to the frame, a link having one end pivoted to said part, a second link pivot-
20 ally connected to the other end of the first named link and to said member, a bar pivot-
25 ed to the first named link between its pivoted ends and operative to move the same from its normal position and thereby move said member toward said anvil and thereafter move said part, a spring having one end connected to said frame and the other end connected to the first named link between its pivoted ends to return it to normal position,
30 a shaft, a driving member loosely mounted on said shaft, means controlled by said part when moved to start and stop the rotation of the driving member, an eccentric carried by the driving member, an arm operatively
35 connected to the eccentric, and connecting actuating means between said arm and the staple driver.

30 75. In a staple setting machine, a combination of a supporting frame, a staple setting anvil supported by the frame, a member pivoted on the frame to move toward and from the anvil and provided with staple guiding means, a staple driver guided in said member and adapted to coöperate with said anvil to set a staple, a controlling part pivoted to the frame, a link having one end pivoted to said part, a second link pivotally connected to the other end of the first named link and to said member, a bar pivoted to the first named link between its pivoted ends and operative to move the same from its normal position and thereby move said member toward said anvil and thereafter move said part, a spring having one end connected to said frame and the other end connected to the first named link between its pivoted ends to return it to normal position, a shaft, a driving member loosely mounted on said shaft, means controlled by said part when moved to start and stop the rotation of the driving member, an eccentric carried by the driving member, an arm operatively connected to the eccentric, a lever fulcrumed on said arm, a spring acting between a part of the machine and said lever on one side of its fulcrum to move it toward the eccentric, and a lever fulcrumed on the

26. In a staple setting machine, the combination of a supporting frame, a staple setting anvil supported by the frame, a member pivoted on the frame to move toward and from the anvil and provided with staple guiding means, a staple driver guided in said member and adapted to coöperate with said 40 member and adapted to coöperate with said anvil to set a staple, a controlling part pivoted to the frame, a link having one end pivoted to said part, a second link pivotally connected to the other end of the 45 first named link and to said member, a bar pivoted to the first named link between its pivoted ends and operative to move the same from its normal position and thereby move said member toward said 50 anvil and thereafter move said part, a spring having one end connected to said frame and the other end connected to the first named link between its pivoted ends to return it to its normal position, a shaft, a driving member loosely mounted on said shaft, means controlled by said part when moved to start and stop the rotation of the driving member, an eccentric carried by the driving member, an arm operatively connected to the eccentric, a lever fulcrumed on said arm, a spring acting 60 between a part of the machine and said 65 machine and connected to the first named lever on the other side of its fulcrum and operatively connected to the staple driver, whereby when the eccentric is rotated the staple driver will be actuated by a yielding pressure. 105

28. In a staple setting machine, the combination of a supporting frame, a staple setting anvil supported by the frame, a member pivoted on the frame to move toward and from the anvil and provided with staple guiding means, a staple driver guided in said member and adapted to coöperate with said 110 anvil to set a staple, a controlling part pivoted to the frame, a link having one end pivoted to said part, a second link pivotally connected to the other end of the first named link and to said member, a bar pivoted to the first named link between its pivoted ends and operative to move the same from its normal position and thereby move said member toward said 115 anvil and thereafter move said part, a spring having one end connected to said frame and the other end connected to the first named link between its pivoted ends to return it to its normal position, a shaft, a driving member loosely mounted on said shaft, means controlled by said part when moved to start and stop the rotation of the driving member, an eccentric carried by the driving member, an arm operatively connected to the eccentric, a lever fulcrumed on said arm, a spring acting 120 between a part of the machine and said 125 machine and connected to the first named lever on the other side of its fulcrum and operatively connected to the staple driver, whereby when the eccentric is rotated the staple driver will be actuated by a yielding pressure. 130

moved to start and stop the rotation of the driving member, an arm operatively connected to the eccentric, a lever fulcrumed on said arm, a spring acting between 5 a part of the machine and said lever on one side of its fulcrum to move it toward the eccentric, a link pivoted on the frame, and a lever fulcrumed on the link and connected to the first named lever on 10 the other side of its fulcrum and operatively connected to the staple driver, whereby when the eccentric is rotated the staple driver will be actuated by a yielding pressure.

29. In a staple setting machine, the combination of a supporting frame, a staple setting anvil supported by the frame, a member pivoted on the frame to move toward and from the anvil and provided with staple guiding means, a staple driver guided 15 in said member and adapted to coöperate with said anvil to set a staple, a controlling part pivoted to the frame, a link having one end pivoted to said part, a second link pivotally connected to the other end of the first 20 link and to said member, a bar pivoted to the first named link between its pivoted ends and operative to move the same from its normal position and thereby move 25 said member toward said anvil and thereafter move said part, a spring having one end connected to said frame and the other end connected to the first named link between its pivoted ends to return it to normal 30 position, a shaft, a driving member loosely mounted on said shaft, means controlled by said part when moved to start and stop the rotation of the driving member, an eccentric carried by the driving member, an arm operatively connected to 35 the eccentric, and a lever fulcrumed on the machine and operatively connecting said arm and the staple driver.

30. In a staple setting machine, the combination of a supporting frame, a staple setting anvil supported by the frame, a member pivoted on the frame to move toward and from the anvil and provided with staple guiding means, a staple driver guided in 40 said member and adapted to coöperate with said anvil to set a staple, a controlling part pivoted to the frame, a link having one end pivoted to said part, a second link pivotally connected to the other end of the first 45 named link and to said member, a bar pivoted to the first named link between its pivoted ends and operative to move the same from its normal position and thereby move 50 said member toward said anvil and thereafter move said part, a spring having one end connected to said frame and the other end connected to the first named link between its pivoted ends to return it to normal 55 position, a shaft, a driving member loosely mounted on said shaft, means controlled by said part when moved to start and stop the rotation of the driving member, an eccentric carried by the driving member, an arm operatively connected to the eccentric, and a lever fulcrumed on the machine and operatively connecting said arm and the staple driver.

and stop the rotation of the driving member, an eccentric carried by the driving member, an arm operatively connected to the eccentric, a link pivoted on the frame, and a lever fulcrumed on the link and operatively connecting said arm and the staple driver. 70

31. In a staple setting machine, the combination of a supporting frame, a staple setting anvil, staple supplying and guiding means, a staple driver adapted to coöperate with said anvil to set a staple, a shaft, a rotatable driving part carried by the shaft and adapted to be constantly driven, a driving member loosely mounted on the shaft, a controlling part mounted on the frame and movable from and to a normal position, a link pivoted to said controlling part, means adapted to act upon said link to move the controlling member from and to its normal position, means operated by the controlling member when moved from normal position to start the actuation of the driving member by said driving part, means operated by the controlling member when returned to normal position to stop the actuation of the driving member after it reaches a predetermined position, and connecting actuating means between the driving member and the staple driver. 95

32. In a staple setting machine, the combination of a supporting frame, a staple setting anvil, staple supplying and guiding means, a staple driver adapted to coöperate with said anvil to set a staple, a shaft, a rotatable driving part carried by the shaft and adapted to be constantly driven, a driving member loosely mounted on the shaft, a controlling part mounted on the frame and movable from and to a normal position, a link pivoted to said controlling part, means adapted to act upon said link to move the controlling member from and to its normal position, means operated by the controlling member when moved from normal position to start the actuation of the driving member by said driving part, said controlling member having a part adapted to engage a part of the driving member to stop the rotation thereof when the controlling member is returned to normal position, and connecting actuating means between the driving member and the staple driver. 100

33. In a staple setting machine, the combination of a supporting frame, staple guiding means, a staple driver, a staple setting anvil having a round part projecting therefrom and into a round opening in the frame at an angle relatively to the plane of the staple driver, said anvil being adjustable 115 about the axis of said part to set the anvil in operative relation to the staple driver, and means to secure said part in adjusted position. 120

34. In a staple setting machine, the com- 130

bination of a supporting frame, staple guiding means, a staple driver, a staple setting anvil having a round part extending therefrom and into an opening in the frame
5 at an angle relatively to the plane of the staple driver, said part being adjustable both longitudinally and about its axis to set the anvil in required adjusted relation to the staple driver, and means to secure said
10 part in adjusted position.

In testimony whereof, I have hereunto affixed my signature this 31st day of October, A. D. 1919.

ELWOOD H. MICHENER.
